US00D943102S

(12) **United States Design Patent** (10) **Patent No.:** **US D943,102 S**
(45) **Date of Patent:** **** Feb. 8, 2022**

(54) **PATELLA PAD**

(71) Applicant: **Ossur Iceland ehf**, Reykjavik (IS)

(72) Inventors: **Sindri Pall Sigurdsson**, Reykjavik (IS);
Bjorn Omarsson, Reykjavik (IS);
Marcel Jansen, Reykjavik (IS); **Liza A. Boon**, Reykjavik (IS)

(73) Assignee: **OSSUR ICELAND EHF**, Reykjavik (IS)

(**) Term: **15 Years**

(21) Appl. No.: **29/706,169**

(22) Filed: **Sep. 18, 2019**

Related U.S. Application Data

(62) Division of application No. 29/627,400, filed on Nov. 27, 2017, now Pat. No. Des. 863,567.

(57) **CLAIM**

The ornamental design for a patella pad, as shown and described.

DESCRIPTION

FIG. 1 is a perspective view of a patella pad.

FIG. 2 is a front elevational view according to the patella pad of FIG. 1.

FIG. 3 is a rear elevational view according to the patella pad of FIG. 1.

FIG. 4 is a first side elevational view according to the patella pad of FIG. 1.

FIG. 5 is a second side elevational view according to the patella pad of FIG. 1.

FIG. 6 is a top plan view according to the patella pad of FIG. 1; and,

FIG. 7 is a bottom plan view according to the patella pad of FIG. 1.

1 Claim, 5 Drawing Sheets

US D943,102 S
